US0D1024974S

(12) **United States Design Patent** (10) **Patent No.:** **US D1,024,974 S**
(45) **Date of Patent:** **** Apr. 30, 2024**

(54) **BUSBAR**

(71) Applicant: **Intel Corporation**, Santa Clara, CA (US)

(72) Inventors: **Samantha Rao**, Bangalore (IN); **Harish Jagadish**, Bangalore (IN); **Arvind S**, Bangalore (IN)

(73) Assignee: **Intel Corporation**, Santa Clara, CA (US)

(**) Term: **15 Years**

(21) Appl. No.: **29/793,027**

(22) Filed: **Jul. 12, 2021**

Related U.S. Application Data

(63) Continuation of application No. 29/675,741, filed on Jan. 4, 2019, now Pat. No. Des. 924,810.
